CLAIM

The ornamental design for a nebulizer-humidifier bag assembly, substantially as shown and described.

DESCRIPTION

FIG. 1 is a front elevation of a nebulizer-humidifier bag assembly showing my new design;

FIG. 2 is a right side elevation thereof;

FIG. 3 is a rear elevation thereof;

FIG. 4 is a top plan view thereof; and

FIG. 5 is a bottom plan view thereof.

FIG. 3.

FIG. 5.

FIG. 2.

FIG. 1.

FIG. 4.
